UNITED STATES PATENT OFFICE

153,922

DESIGN FOR AN EAR SPATULA

Nicholas F. Brignola, Troy, N. Y.

Application May 20, 1947, Serial No. 139,162

Term of patent 14 years

(Cl. D83—1)

To the Commissioner of Patents:

Be it known that I, Nicholas F. Brignola, a citizen of the United States, residing at Troy, in the county of Rensselaer and State of New York, have invented a new, original, and ornamental Design for Ear Spatulas, of which the following is a specification, reference being had to the accompanying drawing, forming part thereof.

Figure 1 is a perspective view looking toward one side of an ear spatula, embodying the new design;

Figure 2 is a perspective view looking toward the other side thereof; and

Figure 3 is an edge view thereof.

I claim:

The ornamental design for an ear spatula, as shown.

NICHOLAS F. BRIGNOLA.
